UNITED STATES PATENT OFFICE

ARTHUR J. BRANSTAD, OF EAU CLAIRE, WISCONSIN

DESIGN FOR A RAZOR-BLADE-VENDING-MACHINE CASING

Application filed September 15, 1930. Serial No. 36,973. Term of patent 14 years.

To all whom it may concern:

Be it known that I, ARTHUR J. BRANSTAD, a citizen of the United States, residing at Eau Claire, in the county of Eau Claire and State of Wisconsin, have invented a new, original, and ornamental Design for a Razor-Blade-Vending-Machine Casing, of which the following is a specification, reference being had to the accompanying drawing, forming part thereof.

The figure is a perspective view of a razor blade vending machine casing showing my design.

I claim:

The ornamental design for a razor blade vending machine casing, as shown.

Eau Claire, Wisconsin, September 11th, 1930.

ARTHUR J. BRANSTAD.
